Patented May 7, 1912.

UNITED STATES PATENT OFFICE.

WILLIAM G. KIRCHHOFF, OF ST. LOUIS, MISSOURI.

WEDGE-KEY.

1,025,278.

Specification of Letters Patent.

Patented May 7, 1912.

Application filed July 24, 1911. Serial No. 640,187.

To all whom it may concern:

Be it known that I, WILLIAM G. KIRCHHOFF, a citizen of the United States, residing at St. Louis, Missouri, have invented a certain new and useful Improvement in Wedge-Keys, of which the following is a full, clear, and exact description, such as will enable others skilled in the art to which it appertains to make and use the same, reference being had to the accompanying drawings, forming part of this specification, in which—

Figure 1 is a sectional view showing a wedge key of my improved construction in position between a shaft and a hub or collar positioned on said shaft. Fig. 2 is a section taken on the line 2—2 of Fig. 1. Fig. 3 is an elevation of a shaft provided with a key way or recess adapted to receive a wedge key of my improved construction. Fig. 4 is a sectional view similar to Fig. 1 and showing a modified form of the wedge key. Fig. 5 is a vertical section taken on the line 5—5 of Fig. 4.

My invention relates to that class of devices known as wedge keys and which are ordinarily employed in locking hubs, collars and sleeves to a shaft or spindle.

The object of my invention is to produce a simple, inexpensive wedge key, which is adapted to be seated in a specially formed key way or recess in a shaft or spindle, and which wedge key and key way are formed so that the wedge key will automatically adjust itself in the key way or seat when forced thereto, and into the groove or key way formed in the hub, sleeve or collar, that is locked by said wedge key.

A further object of my invention is to provide a simple wedge key particularly adapted for use in a key way or seat which can be easily and quickly formed in a shaft or spindle without the use of a special form of cutting tool.

My invention consists in a wedge key which is approximately square in cross section, and which has two of its faces curved throughout their length, thus forming a key body which tapers toward both ends, and which key is utilized in connection with a key seat having a pair of opposite, longitudinally curved inclined faces.

To the above purposes my invention consists in certain novel features of construction hereinafter more fully described and claimed.

Referring by numerals to the accompanying drawing, 1 designates a shaft or spindle in which is formed the key way or seat for my improved wedge key. This key way or seat 2 is in the shape of an oval having pointed ends and the surfaces 3 forming the bottom of said key way or seat curve gradually throughout their entire length, and said surfaces are formed on angles of approximately 90° relative to one another. Thus a key way or seat is formed having two gradually curved, oppositely inclined faces, and which key way has the greatest depth at its center and gradually tapers toward its ends.

4 designates the hub or collar which is locked upon the shaft 1 by means of my improved wedge key and formed within the opening in said hub or collar is a longitudinally disposed V shaped groove 5 of slightly tapering depth throughout its length. The faces forming the bottom of this groove are arranged on angles of approximately 90° with respect to each other, and the greatest width of this groove 5 equals the greatest width of the key way or seat 2.

My improved wedge key 6 as shown, is in the form of an elongated metal block substantially square in cross section, and having a pair of straight plane longitudinally extending upper faces 7 which when the key is properly seated bear against the corresponding faces of the groove 5. The lower faces 8 of the wedge key curve gradually throughout their length and said curved faces bear against the corresponding curved faces 3 forming the bottom of the key way 2 when the key is properly positioned between the shaft and hub. The curved lower faces 8 of the key bearing directly against the corresponding curved faces 3 of the key seat permit the key to automatically adjust itself when being positioned between the shaft and hub, and when the hub is driven to a tight position on the shaft, the greater portion of the key is inclosed by said hub, and it is, therefore, impossible for the key to become accidentally displaced from its seat.

In the modified construction shown in Figs. 4 and 5, the key seat is provided at its center with a pair of vertically disposed parallel faces 9, the lower edges of which join the inclined faces 3, and where such form of key seat is provided the key is provided on its sides with corresponding flat parallel side faces 10 between the faces 7 and 8. In this modified construction a spe-

cial form of cutter or tool is necessary to form the key seat, whereas, in the preferred construction the key seat can be easily and quickly formed with an ordinary angular 5 rotary cutter.

- My improved wedge key is comparatively simple, can be utilized wherever it is necessary to lock a hub, collar or sleeve to a shaft or spindle, is very effective in use, and by 10 the formation of the curved faces in the bottom of the seat, and on the under side of the key, said key automatically adjusts itself in the seat when inserted between the shaft and hub.
15. It will be readily understood that minor changes in the construction and combination of the various parts of my device may be made and substituted for those herein shown and described, without departing from the 20 spirit of my invention, the scope of which is set forth in the appended claims.

I claim:

1. The combination with a shaft in which is formed a key seat that is provided with a 25 pair of inclined faces arranged at an angle of approximately 90 degrees apart, which faces are gradually curved throughout the length of the key seat so that said key seat gradually decreases in depth and gradually 30 tapers in width toward its ends, of a hub adapted to be positioned on said shaft, which hub is provided with a V-shaped groove, the faces of which occupy planes approximately 35 90° apart, and a wedge key adapted to be inserted in the coinciding groove and key seat, which key is provided on its underside with a pair of inclined faces that are curved

lengthwise, and which are adapted to fit against the corresponding faces of the key seat in the shaft, and which key is provided 40 on its upper side with a pair of oppositely inclined straight faces adapted to coöperate with the corresponding faces of the V-shaped groove in the hub.

2. The combination with a shaft having a 45 key seat that is substantially V-shaped in cross section and the oppositely inclined faces of which are gradually curved throughout their length, and a hub or collar having a V-shaped groove, of a wedge key 50 adapted to be inserted in the coinciding key seat and V-shaped groove, which wedge key is provided with a pair of longitudinally disposed straight faces that coöperate with the corresponding faces of the V-shaped 55 groove in the hub, and said key being provided with a pair of oppositely disposed, longitudinally curved faces that coöperate with the faces of the key seat in the shaft.

3. As a new article of manufacture a 60 wedge key comprising an elongated metal block having a pair of straight faces arranged at an angle of 90° apart, and also having a pair of faces that are curved throughout their length, which curved faces 65 are arranged at an angle of 90° apart.

In testimony whereof I hereunto affix my signature in the presence of two witnesses, this 22nd day of July, 1911.

WILLIAM G. KIRCHHOFF.
